BOTTLE CARRIER

Edwin L. Arneson, Morris, Ill., assignor to Morris Paper Mills, Chicago, Ill., a corporation of Illinois

Application January 15, 1947, Serial No. 722,123

5 Claims. (Cl. 229—28)

1

This invention relates to improvements in an article carrier, and in particular to an inexpensive paperboard carrier adapted for use in transporting a plurality of bottles arranged in rows on either side of a central suspending member.

It is an object of the invention to provide a carrier of the type described which is fabricated from a one-piece paperboard blank using a minimum of stock, and which has novel provisions facilitating the manufacture thereof, as well as for imparting added strength and resistance to tearing or destructive distortion in use.

Another object is to provide an improved article carrier characterized by a strong, central, multiple-ply partition and suspending member or panel, at which the filled carrier is grasped or suspended, and a row of article receiving cells on either side thereof, said carrier having improved means for strengthening the walls of the carrier adjoining opposite ends of said panel, so as to resist tearing under load stresses borne through the walls and panel.

Yet another object is to provide a carrier of the type described including opposed end and side walls, a medial partition and suspending panel, and partition elements cut from the material of a pair of the opposed walls and from said panel which serve to subdivide the space on opposite sides of the latter into separate article receiving cells, said carrier being fabricated from a one-piece paperboard blank of a novel design greatly facilitating and expediting the operations of folding and gluing the carrier.

More specifically, it is an object of the invention to provide a bottle carrier having a rigid central triple-ply partition and suspending panel, plus flexible transverse division strips arranged in a vertically stepped or staggered order and subdividing the space on opposite sides of the panel into bottle receiving cells, said panel being integrally connected to said strips and to certain walls of the carrier and said last named walls having an improved reinforced construction to resist rupture or tearing under load stresses transmitted through the panel, the partition and suspending panel comprising a pair of full width panels between which flaps hinged to the panel ends are disposed in face to face contacting relation.

The foregoing statements are indicative in a general way of the nature of the invention, but other and more specific objects will be apparent to those skilled in the art upon a full understanding of the construction and operation of the device.

2

A single embodiment of the invention is presented herein for purpose of exemplification, and it will be appreciated that the invention is susceptible of incorporation in other modified forms coming equally within the scope of the appended claims.

In the drawings,

Fig. 1 is a plan view of a blank from which the carrier is fabricated in accordance with the invention;

Fig. 2 is a plan view illustrating the blank of Fig. 1 in preliminarily folded and glued condition;

Fig. 3 is a view illustrating the carrier following completion of the folding and gluing of the same, but prior to being set up to operative position;

Fig. 4 is an end view of the carrier showing in dotted lines a number of bottles positioned therein;

Fig. 5 is a view in side elevation further illustrating the construction;

Fig. 6 is a view in section on a line corresponding generally to line 6—6 of Fig. 4, further illustrating the arrangement of the parts; and

Fig. 7 is a further sectional view taken on a line corresponding to line 7—7 of Fig. 5.

This invention pertains to improvements in a bottle or like article carrier of the type illustrated and described in the patent to Lebold No. 2,389,318, dated November 20, 1945. The patented carrier is fabricated from a one-piece blank which is slit, creased and folded to provide a central suspending and partition panel connected to opposed side walls on either side thereof by a plurality of partition straps which are cut from the material of respective walls and the panel in a vertically staggered relationship. These straps, in the erected condition of the carton, serve to subdivide the space between the walls and partition panel into two parallel rows of article receiving cells. Reference may be made to the above identified patent for a full description of the construction and advantages of the Lebold type carrier.

In the manufacture of carriers of the type described above it sometimes happens that the slitting of the carrier blank to form the referred to partition straps tends to interfere with a smooth and continuous advance of the blanks from a stack thereof for the folding and gluing operations. Inasmuch as the blanks are fed through the folding and gluing machine in a direction normal to the length of the slitting which defines said straps, when a blank such as that

shown in the patent is employed, the straps tend to engage and catch or snag against one another in the feeding operation and as a result sometimes cause a break in the order of the advancing articles through a conventional type gluing and folding machine. This requires the personal attention of the operator and reduces the output of the machine.

It has also been noted that under heavy loads or rough handling there is a possibility of lateral tearing in the end walls of the referred to holder, at their junction with the partition and suspending panel, since this is the point at which the main load stresses of the filled carrier are transmitted between the body thereof and the panel. While these objections in the previous carrier are more or less minor, nevertheless the present carrier embodies novel features eliminating the same, while preserving all of the very material advantages of the patented structure. In addition, an increased rate of production is made possible, using a standard and well-known type of gluing and folding machine.

Generally considered, the blank from which the present article is fabricated enables the feeding thereof through the gluing and folding machine in a direction paralleling the direction of the slits which define the vertically spaced partition straps of the carrier, which the present article has in common with the patented carrier. Moreover, the construction is such as to afford a double-ply reinforcing thickness of the end wall immediately adjacent the transverse upper slotted edge of said wall, along which the central partition panel is cut therefrom, thereby defining a protective ply transversely overlying or straddling the line along which tearing overload might be expected. Notwithstanding the fact that such theoretical tear line parallels the grain of the stock, the carrier is guaranteed against damage at this point, even under above-normal loads.

Referring to the drawings, in Fig. 1 I illustrate the blank from which one form of the carrier is fabricated. This is die cut in a generally rectangular outline from a suitably stiff but flexible grade of paper board stock. Said blank is provided with a longitudinal fold or crease line 12 on which the blank is subsequently bent, in a manner to be described, to provide a multiple-ply partition and suspending panel, as well as to superpose the sides of the blank and produce the finished knock-down article.

The blank includes two similar, rectangular wall portions 13, 14, and said portions have end wall reinforcing flaps or panels 15, 16, respectively, bendably connected thereto along the fold or crease lines 17 which extend at a right angle to the medial line 12. Said fold lines 17 define end margins for the rectangular portions 13, 14 and coincide with a pair of the diagonally opposed corners of the finished and erected carrier, as will appear.

Bottom defining members are bendably connected to the side margins of the portions 13, 14 as by a fold or crease line 18 paralleling the medial fold line 12. In the case of the portion 13 said bottom defining means consist of an end bottom flap 20 and a pair of adjacent locking tabs 21, 22 which are separated from each other by a transverse slit 23 and from the bottom flap 20 by a transverse slit. In the case of the portion 14, the bottom defining means consist of an end bottom flap 25, similar to the flap 20, and a further flap 26 separated therefrom by a transverse slit. Flap 26 is provided with a longitudi-

nally extending locking slot 28 adapted to receive certain oppositely extending locking ears 29 which are formed on the tabs 21, 22, after the various tabs and flaps have been folded inwardly across the bottom of the carrier, in a well-known fashion. This bottom defining structure is old and well known in the art and does not constitute a part of the present invention.

The rectangular side portions 12, 14 of the blank are provided with certain slits and creases, which are identical but in inverted relation in the respective portions. Said slits and creases serve to subdivide the said portions of the blank and to in part define therein the pairs of integral connected, opposed end and side walls of the carrier, along with a longitudinally extending central partition and suspending panel and certain transverse straps. Such straps are arranged in a vertically stepped relationship to extend between the panel and the side walls so as to subdivide the space on opposite sides of said panel into article receiving cells.

To the above ends, the portions of the blank on opposite sides of crease 12 are each provided with a set of three elongated, parallel slits, hereinafter more fully described, arranged in a laterally spaced, longitudinally overlapped relation, paralleling and spaced from the medial fold line 12. The slits are in equally overlapped relation to one another. They extend completely through the material of the blank and are intersected by certain fold lines or creases, hereinafter described more fully, to separate each of the portions 13, 14 into side and end wall panels, specifically designated 33, 34, respectively and to define various co-acting elements.

The above referred to creasing includes the transverse creases 35 which are located in alignment with the flap defining slits 24, 27, respectively, and constitute fold lines hingedly articulating the aforesaid side and end wall panels 33, 34. Accordingly, they will be disposed at diagonally opposite corners of the carrier in the erected, operative position thereof.

The respective sets of slits referred to above separate the above referred-to wall panels from longitudinal partition and suspending panels 36 on opposite sides of the medial fold line 12; and they also serve to define three transverse partition straps on either side of said line.

In completing the carrier from the thus scored and slotted blank, the same is fed through a conventional gluing and folding machine, in a direction paralleling the direction of the sets of strap-defining creases described above, so that there is no tendency for the straps to snag against one another and impede the operation of the apparatus.

As an additional feature, the carrier under consideration is provided with end flaps 50, 51 bendably conjoined to opposite ends of the partition and suspending panels 36 along a transverse fold line 52. Said end flaps 50, 51 are separated from the carrier end walls 34 by slits 53. Mating hand holes 54 are defined in the respective panels 36 by the U-shaped slits 55 and the connecting creases 56, and the panels 50, 51 are provided with similarly shaped and located notches or recesses 57 adapted to register with the aforesaid openings 54 when the panels are folded over on lines 52 into superposed relation to the respective partition and suspending panels 36. The straps referred to above are denoted 69 and are formed in the blank in the following fashion.

Parallel, longitudinally overlapped and lateral-

ly spaced slits 58, 59 are provided in the portions 13, 14 of the blank, the latter of which is intersected at one end by a transverse fold crease 60 in end wall panel 34. Said crease is located at the midpoint in the width of panel 34 and in alignment with the crease 52 which defines one end of panel 36' in the completed condition of the carrier. Slit 59 is curved at its juncture with crease 60 as indicated at 59' to minimize tearing tendency as hereinafter pointed out. It extends equal distances on opposite sides of fold line 35 and at its opposite end is intersected by a transverse crease 61 in wall 33 which extends in the lateral direction to slit 58. A further aligned crease 62 extends to the top of side wall panel 33, where it is intersected by a slit 63 aligned with slit 53 and coincident with the top of panel 33. Slit 63 serves to separate panel 33 from the central partition and suspending panel 36'.

The slit 58 extends from a crease 64 which is in alignment with corner crease 35 to a point coincident with the end margin of panel 36' where it is intersected by a crease 65 aligned with said margin.

In completing the carrier, the panels 15, 16 are folded over onto the body of the blank and adhesive 66 is applied to the upper surface of the end wall reinforcing panels 15 and 16. The panels 50, 51 are similarly folded over onto the panels 36' respectively, and, preferably, are adhesively secured thereto. The upper exposed surface of the thus folded panels 50, 51 is given a coating of adhesive, as indicated at 67, whereupon the blank is folded along line 12 to bring the portions 13, 14 thereof into superposed, adhesively secured relation, thus producing the finished knocked-down carrier illustrated in Fig. 3.

In this form the carrier is characterized by a multiply partition and carrying panel, generally designated by the reference numeral 68, which is of three-ply thickness throughout the major portion of the area thereof, including the area adjacent the hand holes 54. The presence of this extra material at the load sustaining zone of the suspending member enables the carton to be fabricated in perfectly satisfactory strength either of a light gauge stock or of an inexpensive chip board. Panels 15, 16 inhibit tearing tendency at the end walls, as does also the curved end 59' of slit 59, extending transversely of the grain of the stock.

In use, the tabs defined by the slits 55 in the suspending panel are deflected outwardly to permit access of the user's fingers in the holes 54, thereby bringing the hand and knuckles well down among the necks of the bottles and resulting in a very effective, twist-resistant grasp of the carrier, all as described in detail in the above identified patent to Lebold, No. 2,389,318. The plies of the handle 68 are firmly secured together so that end shifting and resultant instability are impossible. As clearly illustrated in Figs. 4 and 5, the carrier terminates beneath the tops of the bottles disposed therein, enabling a number of the filled carriers to be stacked in vertical relation.

I claim:

1. An article carrier fabricated from a one-piece paperboard blank and comprising a pair of panels defining an upstanding partition member, a lateral flap hinged to an end of each of said panels and folded inwardly to position between the latter, spaced side walls paralleling said member on opposite sides thereof, end walls hinged by vertical creases to end margins of said side walls,

said end walls each including a panel to which one of said partition member panels is hinged by a vertical crease extending only partly of the height of the end wall panel, said flaps being separated by cuts in the blank from the material of said respective end wall panels, division members bendably connected to said respective side walls and member on vertical hinges and adapted to extend between the respective panels and said respective side walls, said division members serving to divide the space on either side of the partition member into cells, said partition member being in fixed vertical relation to said division members and side walls, and means providing a bottom for the carrier connected to said walls.

2. An article carrier fabricated from a one-piece paperboard blank and comprising a pair of panels defining an upstanding partition member, a lateral flap hinged to an end of each of said panels and folded inwardly to position between the latter, said panels being connected to one another by a fold line along the top of said member which is integral with both of said panels, means securing said panels in fixed relation to one another, spaced side walls paralleling said member on opposite sides thereof, end walls hinged by vertical creases to end margins of said side walls, said end walls each including a panel to which one of said partition member panels is hinged by a vertical crease extending only partly of the height of the end wall panel, said flaps being separated by cuts in the blank from the material of said respective end wall panels, division members of integral one-piece construction bendably connected to said respective side walls and member on vertical hinges which are integral with said respective panels and side walls and adapted to extend between the respective panels and said respective side walls, said division members being defined by cuts serving to divide the space on either side of the partition member into cells, said partition member being in fixed vertical relation to said division members and side walls, and means providing a bottom for the carrier connected to said walls.

3. An article carrier fabricated from a one-piece paperboard blank and comprising a pair of panels defining an upstanding partition member, a lateral flap hinged to an end of each of said panels and folded inwardly to position between the latter, said panels being connected to one another by a fold line along the top of said member which is integral with both of said panels, means securing said panels in fixed relation to one another, spaced side walls paralleling said member on opposite sides thereof, end walls hinged by vertical creases to end margins of said side walls, said end walls each including a panel to which one of said partition member panels is hinged by a vertical crease extending only partly of the height of the end wall panel, said flaps being separated by cuts in the blank from the material of said respective end wall panels, division members of integral one-piece construction bendably connected to said respective side walls and member on vertical hinges which are integral with said respective panels and side walls and adapted to extend between the respective panels and said respective side walls, said division members being defined by vertically spaced cuts serving to divide the space on either side of the partition member into cells and being arranged in a relation to one another longitudinally of the partition member and walls such as to define an intermediate cell side wall of height different

from the wall height of cells adjoining the same, said partition member being in fixed vertical relation to said division members and side walls, and means providing a bottom for the carrier connected to said walls.

4. An article carrier fabricated from a one-piece paperboard blank and comprising a pair of panels of substantially equal size defining an upstanding suspending and partition member, said panels being integrally and bendably connected to one another by folding along the top of said member, lateral flaps on said member foldable inwardly from opposite ends thereof between the panels to strengthen and rigidify said member, spaced side walls paralleling said member on opposite sides thereof, end walls hinged by vertical creases to end margins of said side walls, said end walls each including a panel to which one of said partition member panels is hinged by a vertical crease extending only partly of the height of the end wall panel, said flaps being separated by cuts in the blank from the material of said respective end wall panels, division members of integral one-piece construction bendably connected to the respective panels of said member and said respective side walls, said division members being integral with said walls and panels and defined by cuts in the material of the blank from which said side walls and partition member panels are taken and serving to divide the space on either side of the partition member into cells, and means providing a bottom for the carrier connected to said walls.

5. An article carrier fabricated from a one-piece paperboard blank and comprising a pair of panels of substantially equal size defining an upstanding suspending and partition member, said panels being bendably connected to one another by folding along the top of said member, lateral flaps on said member foldable inwardly between the panels to strengthen and rigidify said member, spaced side walls paralleling said

10

15

member on opposite sides thereof, end walls hinged by vertical creases to end margins of said side walls, said end walls each including a panel to which one of said partition member panels is hinged by a vertical crease extending only partly of the height of the end wall panel, said flaps being separated by cuts in the blank from the material of said respective end wall panels, division members of integral one-piece construction bendably connected to the respective panels of said member and said respective side walls, said division members being integral with said walls and panels and defined by cuts in the material of the blank from which said side walls and partition member panels are taken and serving to divide the space on either side of the partition member into cells, and means providing a bottom for the carrier connected to said walls.
